PROCESSES FOR REFINING HYDROCARBON OILS BY MEANS OF HALOGEN COMPOUNDS

Ernst Terres, Berlin, Germany, Josef Moos, New York, and Erich Saegebarth, Jackson Heights, N. Y., assignors to Edeleanu Gesellschaft, m. b. H., a German corporation

No Drawing. Application October 25, 1937, Serial No. 170,964

8 Claims. (CL 196—19)

This invention relates to the refining of hydrocarbon mineral oils, such as petroleum oils, and oils made from coal tar and bituminous coal tar, to improve their qualities for lubrication, motor fuel, solvents and other uses, and is a continuation in part of our application Serial No. 12,528, filed March 22, 1935, for Processes for refining hydrocarbon oils by means of halogen compounds.

For the refining of mineral oils, selective solvents, mixtures of selective solvents or mixtures of a selective solvent with a non-selective solvent are already known. These solvents separate the main groups of hydrocarbons by dissolving for example the aromatic and unsaturated components and leaving undissolved the saturated or paraffine-like groups. Some selective solvents remove also the naphthenes together with the aromatics and unsaturates.

The hydrocarbon compounds belonging to the groups of aromatic and unsaturates and—to a certain degree also those of the naphthalene groups—are well known as non-resistant against oxidation. They are further characterized by a low A. P. I. gravity, low flash and fire point, by high carbon residue and by an unfavorable viscosity-temperature relationship. The removal of the mentioned classes of hydrocarbons results therefore in a greatly improved refined oil which is equal to or in some instances even better, than the best mineral oils known, such as fractions from Pennsylvania crude. Whereas fractions made from Pennsylvania crudes have a satisfactory viscosity temperature characteristic, they show nevertheless high Conradson carbon figures and require consequently expensive refining to yield a finished oil which satisfies modern demand for use in internal combustion engines.

Our invention teaches the use of a selective solvent which produces finished oils of a quality superior to Pennsylvania oils insofar as the viscosity temperature relationship of stocks of any origin is improved to that or above that of Pennsylvania oils and also insofar as the carbon residues are much lower. The extraction by means of our solvent further greatly facilitates the finishing procedure inasmuch as the solvent extraction removes all or most of the color bearing compounds with the extracted fraction.

For reasons of simplicity we will refer in the following to the refined oil as "raffinate" and to the undesirable or extracted fraction as "extract."

An object of this invention is to refine hydrocarbon oils by means of a selective solvent in order to produce stable raffinates which, when

properly finished, will fulfill the most severe specifications adopted by science for the specific products in question.

Our selective solvent is adaptable to the refining of naphthas in which case a saturated fraction or raffinate is produced such as is frequently used as special solvent, for example Stoddard's solvent; and the dissolved fraction or extract contains the aromatic and unsaturated components which have great value on account of their high octane number. These extracts may either be used as motor fuel directly or as a blending material for upgrading other gasolines of less satisfactory specifications.

Likewise our solvent is suitable for refining kerosenes, gasoils, transformer oils, turbine oils, the various grades of lubricating oil distillates and of residual stocks.

Depending upon the stocks to be refined and depending upon the raffinate quality desired, the solvent may be used either alone or in combination with auxiliary solvents. These auxiliary solvents have to fulfill three different objects, namely, that of (1) increasing or (2) decreasing the solvent power or that of (3) improving the selectivity of our selective solvent.

The representatives of class 1 of auxiliary solvents which increase the solvent power are characterized by dissolving hydrocarbon oils entirely and at the same time by being miscible with the selective solvent in each proportion. Examples of this class of auxiliary solvents are the aromatics (such as benzol, toluol, xylol, etc.), hydroaromatics, such as cyclohexane, the non-selective aliphatic and aromatic halogen derivatives, the non-selective ketones, esters, ethers and others.

Representatives of class 2 of auxiliary solvents which decrease the solvent power of our selective solvent, as identified by being miscible with our selective solvent to a certain degree or in any proportion and by not dissolving hydrocarbon oils at all or only to a certain extent. For example, water and alcohols belong to this class of auxiliary solvents.

The members of class 3 of auxiliary solvents which improve the selectivity of our selective solvent, are characterized by dissolving the hydrocarbon oils entirely but they are not miscible in each proportion with the selective solvent. This third class of auxiliary solvents will dissolve the hydrocarbon oils to be treated and, upon adding our selective solvent, will remain mostly in the raffinate phase, whereas the first and second groups of auxiliary solvents (namely those which

are miscible with our selective solvent) will go mainly into the extract phase. Representatives of the third class of auxiliary solvents are, for example, low boiling paraffine hydrocarbons such as propane, butane, etc., or mixtures thereof.

A further object of our invention is to remove wax either from the untreated stocks to be refined or from the raffinates, in case that wax-containing stocks are being processed. Our solvent, when blended with a suitable percentage of representatives of class 1 or class 3 of auxiliary solvents mentioned above, constitutes a very good blend for dewaxing inasmuch as these blends dissolve at reduced temperatures only the liquid hydrocarbons but leave undissolved the solid paraffine-like constituents. The removal of the solid paraffine-like constituents, generally termed wax, may be effected either by cold settling, filtration or centrifuging. The procedure becomes especially advantageous if the extraction step is combined with the dewaxing step in any desired order. For example, if the extraction is carried out first, our selective solvent may be used either alone or in combination with one or more representatives of the three classes of auxiliary solvents mentioned above, the raffinate solution, that is the undissolved layer, being saturated with the solvent used for extraction is not charged to the solvent recovery system but is immediately dissolved in an additional amount of a blend of the selective solvent with one or more auxiliary solvents of class 1 or class 3. The quantities of selective solvent and auxiliary solvent or solvents have to be selected in such manner that separation into liquid phases will not take place at the temperature at which the dewaxing is carried out.

We have found that tetrabromoethane possesses an especially good selectivity and at the same time excellent solvent power, and this solvent is therefore especially adapted for refining of hydrocarbon oils. A further advantage of this solvent, as compared with other known selective solvents, is given by its unusually high specific gravity, which results in a much larger difference of gravity between the two layers and consequently the separation of raffinate and extract layer is greatly facilitated. The use of centrifuges for this purpose, necessary for many other known solvents, is therefore eliminated and moreover the settling time is much less than with the other known solvents.

For carrying out our invention, for example in case of treating a waxy stock, we charge the stock to be treated to a countercurrent refining system (comprising three or more mixing and settling stages), and introduce tetrabromoethane at the opposite end of the unit. In this operation the undesirable fractions of the stock are dissolved by the counter current washing action and the raffinate is left in undissolved form containing a certain percentage of the solvent. The solvent quantities which we use and the treating temperatures depend upon the nature of the stock and upon the quality of the raffinate desired. Normally we employ from 100 to 150% of the solvent. The extract layer is charged to the solvent recovery system. The raffinate layer is dissolved in a blend of the same solvent that was employed for the extraction, with a mixture of equal volumes of benzol and toluol or with one or more auxiliary solvents of the above classes 1 and 3. The composition of the solvent blend, containing the selective solvent plus the auxiliary solvent or solvents, is selected in such a manner that sepa-

ration into two liquid phases does not occur at reduced temperatures. We employ from 50 up to 300% of solvent blend. The dissolved raffinate layer is cooled to about -10° F. upon which the wax separates out. The removal of the wax may be effected by cold settling, filtration or by centrifuging.

The filtered solution is charged to the solvent recovery system of the dewaxing part of the combined unit in which the solvents are regenerated for further use. From the solvent blend, recovered in the dewaxing unit, we segregate the selective solvent employed in the extraction part of the plant and recycle it to the extraction plant so as to make up the solvent that was carried over to the dewaxing plant with the waxy raffinate solution. The refined and dewaxed oil is treated with a small amount of clay either by contacting or percolating. The finished oil is of extremely good quality as shown by high A. P. I. gravity, high viscosity index, high resistance against oxidation, low carbon residue, low pour point and good and stable color.

The raw or slack wax is further processed for production of pure petrolatum. For this object we wash the wax cakes with additional quantities of solvent blend or re-extract the slack wax with a suitable composition of the same solvent mixture. By this re-extraction we remove the impurities, that is the liquid hydrocarbons, from the wax.

If deemed advantageous, we may use our selective solvent in combination with an auxiliary solvent either to increase or to decrease the solvent power or to improve the selectivity as described above.

The solvent blend of our selective solvent with representatives of the auxiliary solvents belonging to classes 1 or 3, as mentioned above, may also be used for dewaxing alone independent from the extraction process.

Instead of recovering the solvents from the hydrocarbon groups by distillation we sometimes effect this separation by washing with a different solvent in which our selective solvent is soluble but not the hydrocarbons.

As specific examples for further demonstration of our invention, we cite the following.

Example 1

100 volumes of a Mid-Continent dewaxed distillate are agitated with 100 volumes s-tetrabromoethane ($\text{CH}_2\text{Br}_2\text{CH}_2\text{Br}_2$) at 36° F. The liquids are then allowed to settle after which the lower or extract layer is withdrawn. The treatment is then repeated twice with 50 volumes s-tetrabromoethane under the same conditions. The tetrabromoethane is removed from raffinate and extract layer by distillation under reduced pressure. The raffinate is contacted with clay at 450° F. The results are comprised in the following table:

	Untreated stock	Finished raffinate
Raffinate yield, percent by volume	100	73
^a A. P. I.	23.2	28.8
Viscosity at 100	1237	665
Viscosity at 210	91	73.0
Viscosity index	76	99
Pour, $^{\circ}$ F.	0	+10
Carbon residue	1.9	0.20
Color N. P. A.	Dark.	54

Example 2

100 volumes of a Mid-Continent residual oil are agitated with 150 volumes of s-tetrabromoethane at 80° F. After separation of the two layers, the 5 extract solution is removed and the undissolved portion is treated again with 50 volumes s-tetrabromoethane at 80° F. Again the solvent is recovered from the products by distillation under vacuum, and the raffinate is contacted with clay. 10 The degree of improvement obtained may be seen from the following table:

	Untreated stock	Raffinate
15 Raffinate yield, percent by volume.....	100	34
°A. P. I.....	20.0	27.7
Viscosity at 130.....	997	440
Viscosity at 210.....	145	93
Viscosity index.....	78	95
Carbon residue.....	5.6	1.22

Example 3

25 100 volumes of the same stock as used in Example 2 are dissolved in 100 volumes heptane and the mixture is extracted with 125 plus 75 volumes s-tetrabromoethane at 40° F. in two steps in the same manner as above. The raffinate is then 30 contacted with clay. The presence of heptane raised the yield considerably as shown by the following specifications of the refined oil:

Raffinate yield, per cent by volume.....	74
°A. P. I.....	24.9
35 Viscosity at 130.....	520
Viscosity at 210.....	101
Viscosity index.....	93
Carbon residue.....	2.3

Example 4

40 One volume of a Persian, wax-free mineral oil distillate was extracted respectively at +5° F. with an equal volume of

- (a) Sym. tetrabromoethane
- 45 (b) Tetrabromoethane-benzol blend, containing 15 vol. percent benzol.
- (c) Tetrabromoethane-methanol blend, containing 10 vol. per cent methanol.

50 The effect, in solvent extraction, of benzol and methanol as representatives of classes (1) and (2) of our auxiliary solvents respectively will be seen from the following table:

	Untreated distillate	Raffinate (a)	Raffinate (b)	Raffinate (c)
55 Yield volume, percent.....	100	67	61	68
°A. P. I.....	17.5	23.1	24.3	23.0
60 Saybolt viscosity at 210° F.....	121	88.4	84.2	88.4
Viscosity index.....	47	80	87	79

65 The examples describe treatments made by multiple batch extraction and they serve mainly for demonstrating the refining effect of our solvents. In commercial operation the counter current method of extraction will be used employing either a mixing and settling tank equipment or a so-called tower mixer.

70 We claim the following as our invention:

1. A method of separating dissimilar constituents of lubricating oil and wax made therefrom comprising mixing the oil product with tetrabromoethane at a temperature at which part of

the oil only is dissolved, separating out the undissolved part of the oil solution, and recovering the solvent from the oil solution.

2. A method of refining a mineral oil comprising extracting the oil with tetrabromoethane as 5 a selective solvent to produce a separation into two liquid phases containing respectively paraffinic and non-paraffinic constituents, separating the phases from each other and recovering the solvent therefrom.

10 3. A method of refining a mineral oil comprising mixing the oil with tetrabromoethane as selective solvent and adjusting the temperature to produce a separation into two oil containing 15 phases, separating the phases from each other and recovering the solvent therefrom.

4. A method of refining a mineral oil comprising extracting the oil with tetrabromoethane as 20 a selective solvent in admixture with an auxiliary solvent to produce a separation into two liquid phases containing relatively paraffinic and non-paraffinic constituents, separating the phases from each other and recovering the solvents therefrom.

25 5. A method of dewaxing a mineral oil comprising dissolving the oil in a mixture containing tetrabromoethane as a selective solvent and an auxiliary solvent of the class of benzol and its homologues, said solvents being used in such proportions as not to produce a separation into two 30 liquid layers at the dewaxing temperature, cooling the oil-solvent mixture to below the desired pour point whereby the wax precipitates out, removing the wax from the oil-solvent solution and recovering the solvents from the dewaxed oil 35 solution and from the wax.

6. A method of producing lubricating oil of high viscosity index and low pour point comprising extracting the oil in accordance with claim 2, adding to the raffinate so obtained before recovery of solvent therefrom, further amounts of tetrabromoethane and an auxiliary solvent of the class of benzol and its homologues in such proportion as not to produce a separation into two liquid layers at the dewaxing temperature, 45 cooling the mixture to below the desired pour point whereby the wax precipitates out, removing the wax from the oil-solvent solution and recovering the solvents from the dewaxed oil solution and from the wax.

50 7. A method of producing a lubricating oil of high viscosity index and low pour point comprising dewaxing the oil in accordance with claim 5, adding to the dewaxed oil mixture so obtained, before recovery of solvent therefrom, a further amount of tetrabromoethane to produce a separation into two liquid phases containing relatively paraffinic and non-paraffinic constituents, separating the phases from each other and recovering the solvents therefrom.

55 8. The method of processing wax produced by the method of claim 5 comprising dissolving said wax in a mixture containing tetrabromoethane as a selective solvent and an auxiliary solvent of the class of benzol and its homologues, cooling the mixture to the desired temperature, whereby part of the wax precipitates out, removing said precipitated wax from the remaining solution and washing said precipitated wax with an additional quantity of a mixture of tetrabromoethane and benzol and its homologues.
